5 Claims. (Cl. 200—30)

This invention relates to fuel injection apparatus for internal combustion engines, and more particularly to apparatus wherein fuel is injected into the cylinders of the engine under the control of electromagnetically operated fuel injection valves. The present application is a division of copending parent application Serial No. 136,733, filed by this applicant on April 14, 1937.

In one form of the present apparatus, liquid fuel under pressure is supplied to a fuel chamber delivering into the combustion chamber of each engine cylinder through an orifice normally maintained closed by a movable valve having its stem located in the fuel chamber. A part of the valve stem composed of iron has play within a solenoid, forming an armature therefor, the arrangement being such that, when the solenoid is energized, the valve stem is moved to open the orifice, thus permitting the fuel which, as previously stated, is under pressure, to be injected into the cylinder, whereas, when the solenoid is deenergized, the valve stem under the action of a spring is moved to close the orifice and cut off the fuel supply. There is at least one electromagnetically controlled valve for each engine cylinder.

The invention forming the subject matter of the present divisional application is concerned more specifically with the means for controlling the duration or period of each fuel injection. According to the invention, the control means includes a series of pairs of contacts, one pair for each engine cylinder and each pair being adapted, when and while the contacts thereof are in engagement to complete an electric circuit that energizes the solenoid of the injection valve associated with that cylinder, thereby opening the valve and admitting fuel into the cylinder. When said contacts are disengaged or separated, the circuit is broken and the solenoid deenergized, whereupon the injection valve is closed. Each pair of contacts includes a non-movable contact which is relatively fixed with respect to a ring that surrounds and is concentrically located with respect to the axis of a rotating cam, and an opposite or movable contact arranged on a lever or rocker arm having a fixed pivot and which has an extension portion or follower adapted to engage said cam. A spring urges the rocker arm in a direction to hold the follower on the cam and close the contacts but, because of the cam configuration, the closing is permitted only during a brief portion of the cam's rotation, the rocker arm being normally held against the thrust of the spring during the remaining portion of the cam's

rotation, and in a position wherein the contacts are separated.

Considering that the rocker arm moves from its normal position wherein the contacts are separated and open into its position in which the contacts are closed and then back again to normal position, all in a given angular movement of the cam, it will be apparent that the angular movement can be divided into three stages, namely, (1) that wherein the rocker arm moves from its normal position to the position in which the contacts are closed, (2) that during which the contacts remain closed, and (3) that wherein the rocker arm moves back to its normal position. Such being the case, it can be seen that by varying the first and last stages, the intermediate stage will vary inversely; in other words, if the first and last stages are lengthened, the intermediate stage will be correspondingly shortened; whereas, if the first and last stage are shortened, the intermediate stage will be correspondingly lengthened. In this way is afforded an effective regulation of the time that the solenoid remains energized and, consequently, the period of fuel injection.

In accordance with the present improvements, the regulation referred to is effected by varying the initial or normal distance between the contacts of each pair, or the width of their gap when full open, so that, for any given speed of cam rotation, the period of valve opening and injection is made relatively longer when said distance is decreased and relatively shorter when the distance is increased. This effect is accomplished by turning adjustably the ring or carrier upon which the relatively fixed contacts are mounted, through a limited distance in one direction or the other, depending upon whether the gap between the contacts is to be increased or decreased to shorten or lengthen the injection period. The rotary adjustment of the ring may be accomplished either manually or automatically under control of the engine itself.

These and other specific characteristics of the invention will now be explained with special reference to the drawings which are given merely indicatively as examples, but not limitative as to the scope of the invention.

Fig. 1 is a schematic view of a device embodying the invention, which is suitable for engines operating at relatively low pressures.

Fig. 2 is a schematic view showing the regulating switch hereof in association with an electromagnetically operated valve suitable for two-stroke cycle engines operating at relatively high

pressures, like Fig. 3 of the parent application; the switch being shown in elevation and the valve in vertical section.

Fig. 3 is a sectional view through the switch shown in Fig. 2 taken on the crooked line 3—3 of Fig. 2.

As is shown generally in Fig. 1, the apparatus comprises an electromagnetically governed injector 1 of which there is one for each engine cylinder 2; a current distributor 4 for governing the supply of current from source 3 to the several injectors on the motor, and which varies in its details according to the number of injectors it has to serve; and the fuel feeding supply 5 and pipe 19 delivering under pressure to the several injectors. This apparatus varies according as the injection is to be at low pressure into the air feeding conduits of the motor (motors with separate ignition), or at high pressure into the compression chamber of the motor (motors with spontaneous ignition by compression). Since the invention forming the subject matter of this divisional application is concerned chiefly with the switch controlling the operation of the electromagnetically operated valve, the fuel injection valve selected for illustration is one suitable for use with engines operating at high pressures, although it is to be understood the invention is equally applicable to injection valves for use with engines operating at relatively low pressures as previously stated.

The electromagnetically operated valve illustrated will first be described in detail. Within the valve casing 6 is a cylindrical fuel chamber 16, filled at all times with fuel and which during non-injection periods is maintained closed to the combustion chamber 34, by a valve assembly 7 which slides freely in the casing 6, said assembly 7 comprising a valve stem 7^b of substantially reduced diameter and formed at its left end with a conical valve portion 7^a arranged to engage a valve seat 8 beyond which is the injection orifice 9.

The valve stem 7^b is arranged for limited longitudinal movement in the fuel chamber to effect the opening and closing of the valve, and for this purpose is centrally located and is guided by an enlarged portion 7^c formed in the stem near the left or combustion chamber end thereof, and which portion slides on the inner surface of said cylindrical fuel chamber. The enlarged guiding portion 7^c of the valve stem is formed with a series of longitudinal grooves or liquid displacement passages 18 extending its full length so as, on the one hand to enable the fuel to flow freely past said portion, and, on the other hand, to enable the valve stem to move freely without hindrance by the fuel.

At its opposite or right end, the valve stem is provided with another enlarged portion or head 7^d of magnetic material, as for instance iron, this head having a sliding fit with the valve solenoid 13 and constituting an armature therefor. When the valve is closed, the rightmost end of the enlarged portion 7^d is located in slightly spaced relation, as shown, with a fixed core portion 10 of the solenoid, which core projects inwardly through part of the length of the solenoid from a casing, or shroud 11, which houses the solenoid and is mounted upon the valve casing 6. The portion of the armature or movable core which is carried by the valve stem 7^b is provided with a cylindrical recess 7^e, open at the right end, and in which there is accommodated a restoring spring 12 reacting between the head 7^d and the

fixed core portion 10, the spring constantly urging the valve to its closed position.

Since the solenoid shroud 11 is of magnetic material, there will be a substantially complete path of magnetic material for the flux of the solenoid, broken only by the normal slight gap between the fixed core portion carried by the casing and the movable core or armature carried by the valve stem. Liquid displacement passages 15 at the base of the recess in the armature portion 7^d permit the free flow of fuel between the main valve chamber and the recess 7^e.

According to the arrangement just described, when the solenoid 13 is energized, the armature 7^d carried by the valve stem will be moved instantaneously, against the resistance of the spring 12, in a direction to close the magnetic gap, and this movement will effect an instantaneous and complete opening of the valve so as to allow the discharge of fuel for injection toward or into the combustion chamber 34. Later, when the solenoid is deenergized, the spring 12 will act instantaneously to move the valve to its closed position, thus cutting off quickly the flow of fuel and injection. Because of the liquid displacement passages 15 in the armature and the grooves or liquid displacement passages 18 in the enlarged portion 7^c near the left end of the valve stem, it will be apparent that the valve assembly is in effect floating and freely movable in the liquid fuel, and that there is no pumping action which, on the one hand, would retard the movements of the valve to its opened or closed positions, or, on the other hand interfere with the flow of fuel to the combustion chamber 34 when the valve is opened. The quick closing is enhanced by the fuel outflow in the same direction.

Coming now to the distributor switch 4, the details of which are shown in Figs. 2 and 3, this consists of a series of pairs of contacts, one for each cylinder, each pair comprising contacts 125 and 128 and the several pairs, two being shown, being arranged equidistantly from each other in a series arranged around a cam 122 which is mounted upon a cam shaft 122^a journalled in a support 130 attached to a fixed shell or casing 127. There being one pair of contacts for each cylinder of the engine, the cam 122, depending upon whether the engine operates on the four-cycle or two-cycle principle, rotates at half the speed or at the same speed as the main shaft of the engine. Each pair of contacts includes a relatively fixed contact 128 mounted upon a carrier or annular ring 129 which is seated movably in a groove formed for the purpose in the support 130. Each of the other contacts 125 is mounted at the outer end of a pivoted lever or rocker arm 121, these lever arms being pivoted each upon a pin 123 fixed in the support 130. The relation between each pair of contacts may be initially set by a threaded and nutted mounting 128^a of each non-moving contact 128.

At its inner end, each contact lever 121 has a follower running along the periphery of the distributor cam 122, being pressed by a spring member 124, fixed at one end to the shell or casing and at its opposite end to the outer end of the rocker arm. The spring also may serve as a conductor in each control circuit. Each controlled circuit may extend between grounds M and M, through ring 129, contacts 128 and 125, spring 124, post 126, solenoid 13 or 134 and battery 133.

The rocker arm 121 may be of non-conducting material, or the contact 124 may be insulated thereon, whereas the ring 129 may be an electri-

cal conductor as also the spring 124. Electrically connected to the spring 124 is a binding post 126 from which a conductor extends to the solenoid 13, another lead extending from the solenoid to a source of electrical energy, as, for instance, a battery 3 or 133, the latter in turn being grounded as is also the ring 129. Each contact 125 is electrically connected to the spring 124, and each contact 128 to the ring 129. Consequently, when any contacts 125 and 128 come into engagement, an electrical circuit is completed through the solenoid 13 whereby the latter is energized, thus quickly opening the injection valve for a predetermined duration so as to permit the fuel to be injected into the cylinder for this period as previously described; and when the contacts 125 and 128 become separated, the electrical circuit is broken, thereby deenergizing the solenoid, causing the valve to be closed by the action of the spring 12, and terminating the injection.

The timed opening and closing of the contacts 125 and 128 is controlled from the cam 122. This cam has a general contour portion which may be concentric and will be called the high portion x , also a low portion z , and the two inclines y , y between x and z . When the rocker arm 121 is opposite the high portion x of the cam, the contacts are disengaged, as seen at the right of Fig. 2, whereas when the rocker arm is opposite a low portion z or part of y of the cam, engagement of the contacts is effected by the action of the spring 124 as seen at the left.

The drop y of the cam from its highest portion x to its lowest portion z is gradual as is also the corresponding rise y of the cam. As the cam rotates, it will be apparent that as the rocker arm 121 rides down along the drop y , it will swing under the action of the spring 124 until it is arrested by the engagement of the contacts which then remain closed until the rocker arm is picked up again by the other slant or rise, whereupon the contacts become separated. Thus, the rotation or angular movement of the cam from the time the rocker arm leaves the high portion thereof until the time it is again engaged by the high portion of the cam can be divided into three stages, as previously explained, the intermediate stage (2) being that during which the contacts remain in engagement, a first stage (1) during which the rocker arm moves from its normal position to its contact engaging position and a last stage (3) during which the rocker arm moves from its contact engaging position back to normal position. Consequently if the first and last stages are adjustably varied the intermediate stage will be varied in an inverse manner. That is, assuming a given speed of rotation of the cam, it will require a fixed period or time, or of angular rotation, for the cam to rotate from the position wherein the rocker arm leaves the high portion thereof to the position wherein it again attains the high portion of the cam. It follows from this that the period during which the contacts 125 and 128 remain in engagement will depend upon the time it takes the rocker arm to move at constant speed between its two limits of motion (provided by the cam portion x and the contact 128) since the speed of rocker arm swinging movement does not vary, assuming as previously stated that the cam is rotating at a given speed. Consequently an adjustment of the contact 128 in a direction to widen the normal gap between the contacts will lengthen the time necessary for the rocker arm to move between its extreme positions and consequently will decrease

the period in which the contacts remain in engagement. And conversely, when the contact 128 is shifted in a direction to shorten the gap between the contacts, the time required for the rocker arm to move between its extreme positions will be shortened, and the time of contact engagement will be correspondingly lengthened. In this way, the period of energization of the solenoid 13, and consequently the period of fuel injection, is regulated.

The adjustment of all of the contacts 128 for such regulation is simply and readily effected by adjusting the ring 129 on which the contacts 128 are fixedly mounted. A very slight rotary adjustment of the ring changes substantially the gap between each contact pair. This adjustment of ring 129 is brought about by the following illustrative means. A rockshaft 131, journaled in the casing 121 near the bottom thereof, carries at its inner end an offset or eccentric portion or stud 131^a which enters a slot 129^a formed in the ring 129. An operating handle or arm 132 pinned to the shaft 131 at the outer end thereof forms a convenient device for the rotary adjustment of the shaft 131 to effect the adjustment of the ring. This arm 132 may be either manually controlled or automatically controlled from an engine governor, or by connecting the arm with manometric capsule or other pressure responsive instrument operated for example from the engine intake pressure. Since there is a contact 128 mounted on the ring 129 for each engine cylinder, the period of fuel injection in all of the cylinders will be the same, since all the contacts will partake of the same degree of adjustment, when the shift of handle 132 adjusts the ring.

While in the embodiment disclosed the contacts 128 are those through which regulation is effected, through the ring 129, it will be apparent that the adjustment could be reversely effected equally as well by maintaining the ring 129 fixed and providing instead for the rotary adjustment of the circular member 130.

In the accompanying drawing the invention has been shown merely by way of example and in preferred form, but obviously many variations and modifications may be made therein which will still be comprised within its spirit. It is to be understood therefore that the invention is not limited to any specific form or embodiment, except in so far as such limitations are specified in the appended claims.

What is claimed is:

1. A circuit controller or distributor for a series of electromagnetic actuators adapted to effect the timed closing and interrupting of the circuits of the respective actuators thereby to determine the duration of each energization thereof; said controller comprising for each circuit a pair of contacts having separate supports and normally spaced apart on their supports with a predetermined open gap, an operating member or rotary cam for regularly causing the to-and-fro movement of the first contact on its support across the spacing gap, thereby to close and interrupt the circuit with a predetermined period of closure, and means to adjust one of said supports relatively to the other to vary the normal width of open gap between the two contacts thereby to regulate the period of each closure of circuit and the duration of each energization of actuator.
2. A controller as in claim 1 and wherein the operating member is an open cam with spring-

pressed follower thrust by the cam to retract the movable contact.

3. A controller as in claim 1 and wherein the adjusting means, lever or handle is connected to adjust finely the position of the support of the non-moving contact.

4. A controller as in claim 1 and wherein the operating member is an open cam with spring-pressed follower thrust by the cam to retract the movable contact; the open cam contour having a low part which is out of contact with the follower when the two contacts are in contact, and a high part which holds the contacts spaced apart.

5. A circuit controller or distributor for a series of electromagnetic actuators adapted to effect the timed closing and interrupting of the circuits of the respective actuators thereby to determine the angular duration of each energiza-

tion thereof; said controller comprising for each circuit an active and a passive contact mounted on separate supports, and normally spaced apart on their supports with a predetermined open gap, the support of the several passive contacts being shiftable annularly, a central rotary cam for regularly causing the to-and-fro movement of the active contact on its support across the spacing gap thereby to close and interrupt in sequence the several circuits with a predetermined angular period of closure, and means to adjust annularly said rotarly shiftable support relatively to the other support to vary finely the normal width of open gap between each pair of contacts thereby to regulate the angular duration of each closure of circuit and each energization of actuator.
